SLIDING INDICATOR FOR TRIANGULAR SCALES

Thomas J. Foster, 233 N. Vail Ave.,
Montebello, Calif.

Filed Mar. 1, 1965, Ser. No. 84,010

Term of patent 14 years

(Cl. D52—6)

FIG. 1.

FIG. 2.

FIG. 3.

FIG. 4.

FIG. 5.

FIG. 1 is a plan view of a sliding indicator for triangular scales showing my new design;

FIG. 2 is a side elevation thereof;

FIG. 3 is an end elevation thereof;

FIG. 4 is a bottom plan view thereof; and

FIG. 5 is a perspective view thereof.

The side and end not shown are substantially the same in appearance as the side and end illustrated.

I claim:

The ornamental design for a sliding indicator for triangular scales, as shown and described.
